FOLDING TABLE STRUCTURE

Maurice Hollander, New York, N. Y.

Application October 4, 1946, Serial No. 701,333

2 Claims. (Cl. 311—83)

1

This invention is an improvement in table structure for use with a bathing receptacle the body of which is made of stout textile fabric capable of holding water and mounted upon a suitable framework, the parts of which are movably connected together so that the entire article can be folded into relatively small compass when not needed, and easily distended so as to be set up in readiness for use.

An important object of the invention is to provide a bathing unit chiefly for young children, of simple design, and durable in construction, including not merely the body of the receptacle but also supporting members and a cover therefor, and a rear panel which can be kept elevated at the back of the receptacle, when the cover is down to close it; the cover then serving as a table on which the child can be laid when it is to be dried and dressed; the panel and the cover also being capable of movement rearward into pendant positions below the receptacle when the latter is to be filled with water and used for benefit of its occupant.

The drawings illustrate one embodiment of this invention which is the best form now known to me, and I may, of course, make changes in minor respects without departing from the principle of the invention or exceeding the scope and meanings of the terms in which the appended claims are expressed.

In the drawings,

Figure 1 is a front view in perspective of a folding bathtub according to this invention.

Figure 2 is a side view of the upper part of same, with the cover closing the receptacle and the rear panel secured in position above it, and indicating how both the cover and panel can be swung down to the rear of the unit, and

Figure 3 shows a detail of the device.

The receptacle comprises supporting members, consisting of a pair of legs at each end. Each pair has an inside leg 1 and an outside leg 2 connected at their mid points by a pivot 3. A top or cover is pivoted to the upper ends of the outside legs 2. This cover is made of a frame 4 with cloth 5 stretched over it and secured to all the sides, and can be lifted and lowered about its rear edge as an axis.

When the complete article is to be set up, the legs 1 and 2 are spread apart at their upper and lower ends by movement on the pivots 3, the outside legs 2 are then inclined towards the rear and the inside legs 1 to the front. The tops of the legs 1 are united by a rigidly attached front cross bar 6, and the top of the legs 2 by a similar

bar 7. Between these bars hangs the body of the receptacle 8. This receptacle is made of the pieces of strong cloth joined together and secured to the bars 6 and 7; and when the legs are distended, it is like a trough in cross section but with the ends as well as the sides of the trough closed; the cloth being worked so as to give this shape and effect.

The cloth is corded or otherwise reinforced along the top edges of the ends of the receptacle between the bars 6 and 7, as indicated at 9, particularly in Figure 1, where the cloth 5 is shown removed at the left front corner. The upper parts of the legs 1 and 2 are thus limited in their range of movement away from each other. The lower ends of the legs 1 are connected by braces 10, and so with the legs 2; and all four legs have on their lower extremities rubber tips shown at 11.

20 To the outer face of the upper extremity of each outside leg 2 I affix a mounting plate 12, which is wider than the thickness of the legs 2 from front to back, and extends farther back than the rear face of the leg bearing it; and is bevelled somewhat along the top edge. These plates 12 have one or more lugs 13 projecting at any point where they can be made to fit snugly against either or both the front and back faces of the legs 2. The plates are fastened to the legs in any secure manner. Each of the mounting plates has a pivot stud or journal 14 projecting sideways near the upper rear corner, and which is above the legs 2; these studs enter openings at the rear corners of the frame 4 so that the frame with its cloth 5 is pivotally connected to the legs 2 and can be lifted and lowered. This arrangement is illustrated at the right of Figure 2, and at the right rear corner in Figure 1 where the cloth 5 is shown removed to reveal the pivot or journal 14.

40 When closing the receptacle 8 the top cover consisting of this frame and the cloth 5 rests upon the upper ends of the two legs 1 and the bar 6. The panel 15 is also pivoted at the rear of the article, and it consists of a frame 15 and cloth 16. The frame is fashioned out of a metallic rod, bent into the form of an inverted U, and the ends of this rod are turned inward and inserted into bearing holes 17 at the lower rear corners of the plates 12. This frame can therefore be swung downward, so that it hangs from the plates 12 or moved upward and held in a rearward inclined position by means of fastening devices such as clips 18 affixed at one end to the mounting plates 12 below the studs 14. Each

of these clips 18 has a convex bend or arch 19 therein and the outer end 20 is turned away from the plate 12, so that when the panel is to be held substantially upright, the sides of the U-shaped frame can be forced between the clips and the plates 12 into the recess on the inner face of the clip under the arches 19. To the cloth 16 are sewed pieces forming pockets 21.

When the article is set up as shown in Figure 1, the back panel 15 can be held by engagement with the clips 18 in slanting position at the rear of the receptacle 8 after the frame 4 is lowered to rest upon the front bar 6 and the legs 1. When the receptacle is to be uncovered, the back panel is pushed back to withdraw the sides of the frame 15 from under the clips 18, and then the panel is dropped so that it hangs from the plates 12 in lowered position. Then the frame 4 can also be lifted and turned back and down, so that it hangs from the pivot studs 14. This is all indicated by the broken line positions of the parts 4 and 15 in Figure 2. The receptacle 8 can then be filled with water and the child can be bathed therein.

The front and rear edges of the receptacle also have inside loops 22 secured to the cross bars 6 and 7 to engage and support rods connected along the sides of a piece of canvas or other stout cloth to form a sling so that the child can be laid therein, and the ends of the receptacle 8 can have inside pockets for soap or some other bath accessory, these parts being well known accessories for an article of this kind.

The receptacle as described can be set up at any time, opened and closed, and collapsed after being used, readily and quickly. No special skill is required to manipulate the various members when, for example, the back panel 15 is to be moved up to the position shown in Figure 1, with the frame 4 closing the receptacle 8, or to swing down the panel 15 to the rear and the frame 4 into similar position, as indicated in Figure 2. The parts are so easily operated that there is no likelihood of anything ever getting out of order or damaged by mishandling. All the objects and advantages of the invention are thus assured.

Having described my invention, what I believe to be new is:

1. An article of the kind described, comprising a pair of legs pivotally united adjacent their mid-points, one leg of each pair being inclined forward and the other rearward when the article is set up, means connecting the legs of each pair to limit the spreading thereof, mounting plates attached to the upper ends of the rearward inclined legs, a cloth-filled frame pivoted to said plates to be lowered to rest upon said legs, and another frame pivoted to the plates below the points of attachment of the first-named frame and bearing cloth extended thereon, fastening devices attached to said plates and extending rearward to engage said other frame and hold it in elevated position when the first frame is lowered to rest upon said legs and to release the other frame when the first frame is to be lifted.
2. The article according to claim 1, wherein said plates bear pivot studs for the first-named frame at the upper part, and bearing openings for the ends of the other frame adjacent the lower part, and said fastening devices have the form of clips affixed at the forward end to the plates above said openings and free at the opposite ends which are out-turned, said clips having arched portions forming recesses on their inner faces between said ends to receive and releasably hold the sides of said other frame therein when the first frame is lowered upon said legs, and enable the other frame to be released and swung back and lowered when the first frame is lifted.

MAURICE HOLLANDER.
